REFRIGERATED SHOWCASE

Alois L. Weber, Montrose, and Karl A. Weber,
 Brentwood Heights, Calif., assignors to Weber
 Showcase & Fixture Co., Inc., Los Angeles,
 Calif., a corporation of Delaware

Application April 8, 1946, Serial No. 660,396

9 Claims. (Cl. 62—89.5)

1

This invention relates to refrigerated show cases of the type known as self-service cases having an open top and in which no doors are employed. This particular type of case to which the present invention is directed commonly utilizes a display chamber in which articles of food, such as, for example, meat or fresh vegetables are contained. This display chamber commonly is partially enclosed by transparent partitions which are open at the top to permit ready access to the contents of the chamber. Above the level of the opening and to the rear of the show case is a cooling compartment in which the refrigerant coils are mounted for cooling the air which circulates through the display chamber. This invention is directed to an improved baffle which is positioned between the display chamber and the cooling compartment which comprises an integral structure having parallel spaced baffles defining an air duct therebetween. A primary object of this invention is to provide a baffle structure of this type which includes an air duct for conveying air from the display chamber to the cooling compartment, which baffle structure is pivotally mounted so that it may be swung to an inoperative position in order to give access to the cooling compartment from the front of the show case.

Another object is to provide a baffle structure employing a pair of parallel baffles which are each of insulated construction to minimize conduction of heat therethrough.

Another object is to provide access to the display chamber from the rear of the refrigerator, in order that the supply of meat, vegetables, etc., may be replenished.

Other objects and advantages will appear hereinafter.

In the drawings:

Fig. 1 is a perspective view of a refrigerated show case embodying our invention.

Fig. 2 is an enlarged transverse sectional view taken substantially on the line 2—2 as shown in Fig. 1.

Fig. 3 is an end elevational view showing the rear-opening drawer in partially open position.

Figure 4 is a detailed end view partly broken away showing the hinge connection between the baffle structure and the show case wall.

Referring to the drawings, this invention is embodied in a self-service refrigerated show case having a rear wall 10 of the insulated type joined to an insulated floor 11 along its lower edge. A low front wall 12 extends upwardly from the floor 11 and carries a transparent panel 13 along its upper edge. The rear wall 10 extends up-

wardly above the panel 13 and is joined to an insulated top section 14 which extends forwardly from the wall 10 and carries a depending skirt 15 along its front edge.

5 A baffle structure generally designated 16 is attached to the lower end of the depending skirt 15 by means of releasable fastener elements 17. A baffle structure 16 extends downwardly and rearwardly from the skirt 15 and is supported on a shelf 18 carried by the rear wall 10, and secured in position by pivot bolts 19 to straps 20 secured to the end walls of the show case. A slot 19a in a transverse fin element 26 at the end of the baffle structure receives the pivot bolt 19 and allows sufficient endwise movement of the baffle structure away from the shelf element 18 to enable the baffle structure to assume the horizontal position illustrated by the dot and dash lines 18a, as shown in Figure 2.

10 20 From this description it will be understood that the rear wall 10, top 14, depending skirt 15 and baffle structure 16 cooperate to define a cooling chamber 21. A plurality of refrigerant coils 22 is positioned within the cooling compartment 21 and is secured in position by attachment to the rear wall 10.

15 25 The baffle structure 16 preferably comprises a primary front baffle 23 and a rear baffle 24 laterally spaced therefrom to define an air duct 25 therebetween. The baffles 23 and 24 extend lengthwise of the show case and are integrally connected by a plurality of transverse fin elements 26 at intervals throughout the length of the baffles. Both baffles 23 and 24 are of insulated construction to minimize conduction of heat therethrough. A mirror 27 is preferably mounted on the front side of the primary baffle 23 in order to reflect the contents of the display chamber 28. The display chamber 28 is enclosed by the longitudinal transparent panel 13, the transverse transparent panels 29 and 30, the bottom 11 and the rear wall 10.

20 25 30 35 40 45 50 A perforated rack 31 forms the lower support for the products displayed in the chamber 28 and this rack 31 may be supported in any one of several optional positions upon the supports 32. The supports 32 and the rack 31 are carried by the drawer 40 which is slidably mounted within the showcase upon rails 41. Several such drawers 40 extend across the back side 10 of the showcase, each carrying its own adjustable rack 31. Drawer pulls or handles 42 are provided which may be of any desirable shape or configuration. This provision of rearwardly opening drawers 55 enables a butcher or shopkeeper working behind

the showcase to replenish the supply of meat, vegetables, etc., without going around the showcase to the customers' side.

A drain 33 may be provided in the floor 11 as shown.

In the normal operation of this device the refrigerant tubes 22 cool the air within the compartment 21, thereby increasing the density and causing it to fall downwardly within the compartment 21 and into the rear portion of the display chamber 28. The influx of air in the rear of the chamber 28 requires that an equivalent volume of air be displaced therefrom. This displaced air passes into the lower end of the duct 25 between the baffles 23 and 24 and passes upwardly through the duct 25 into the cooling compartment 21. As the air circulates from the cooling compartment 21 through the display chamber 28, it absorbs heat from the food displayed in the chamber 28 and from conduction through the transparent panels 13, 29 and 30. The air outside the refrigerator is warmer and, hence, of lower density. Accordingly, the influx of air through the open top of the display chamber 28 is negligible. The relatively warmer air within the display chamber 28, which is displaced by the cool air entering the rear of the chamber 28 accordingly does not pass outwardly through the access opening into the chamber, but flows in the direction indicated by the arrows into the lower end of the duct 25 as described.

The ends 34 and 35 of the show case extend forwardly beyond the location of the mirror 27 and a roll edge frontal member 36 extends longitudinally of the case between the end members 34 and 35. The member 36 terminates at a lower edge 37 about the same level as the upper end of the mirror 27. A light source, such as fluorescent tubes 38, may be mounted within the member 36 to illuminate the contents of the display chamber 28 and, also, to light up the transparent panes 39 mounted in the member 36 in front of the fluorescent tubes 38.

It is important to provide easy access to the refrigerant coils 22. This is necessary to provide for inspection of frost accumulation and for maintenance and repairs as well as for cleaning. In the embodiment of this invention, as shown in the drawings, this access to the refrigerant tubes 22 is made possible by the pivotal mounting of the baffle structure 16. By first releasing the fastener elements 17, the entire baffle structure, including the primary baffle 23 and secondary baffle 24 and the connecting transverse fins 26, may be swung outwardly about the pivot bolts 19 until the baffle structure assumes a substantially horizontal position as illustrated in the dot and dash lines 16a in Fig. 2. With the baffle structure in this inoperative position, access may be had directly to the refrigerant tubes 22 from the front of the show case. When the inspection or repairs have been completed, the assembly may be returned to the operative position simply by turning the baffle structure 16 back to its operative position and securing it in such position by the fastener elements 17. It will be apparent that this operation may be effected quickly and easily and without dismantling the show case.

Having fully described our invention, it is 70 to be understood that we do not wish to be limited to the details herein set forth, but our invention is of the full scope of the appended claims.

We claim:

1. In a refrigerated show case, the combination of a display chamber open at the top for access to the contents of the chamber, a cooling compartment positioned within the showcase in a position above and to the rear of the display chamber, cooling means including refrigerant tubes mounted in said cooling compartment, duct means leading from the rear of the display chamber to the front of the cooling compartment for conveying air from display chamber to the cooling compartment, said duct means including an integral structure having spaced parallel baffles extending longitudinally of the show case between the display chamber and the cooling compartment, the pivotal means associated with the duct means near the lower end thereof to permit pivotal movement of the said structure as a unit to an inoperative position to gain access to the cooling means from the front of the show case.
2. In a refrigerated show case, the combination of a display chamber open at the top for access to the contents of the chamber, a cooling compartment positioned within the showcase in a position above and to the rear of the display chamber, cooling means including refrigerant tubes mounted in said cooling compartment, duct means leading from the rear of the display chamber to the front of the cooling compartment for conveying air from display chamber to the cooling compartment, said duct means including an integral structure having spaced parallel baffles extending longitudinally of the show case between the display chamber and the cooling compartment, each of said baffles including a substantial thickness of insulation to minimize conduction of heat therethrough, and pivotal means associated with the duct means near the lower end thereof to permit pivotal movement of the said structure as a unit to an inoperative position to gain access to the cooling means from the front of the show case.
3. In a refrigerated show case, the combination of a display chamber open at the top for access to the contents of the chamber, a cooling compartment positioned within the show case in a position above and to the rear of the display chamber, cooling means including refrigerant tubes mounted in said cooling compartment, duct means leading from the rear of the display chamber to the front of the cooling compartment for conveying air from display chamber to the cooling compartment, said duct means including an integral structure having spaced parallel baffles extending longitudinally of the show case between the display chamber and the cooling compartment, said parallel baffles being staggered so that the front baffle extends above the rear baffle and the rear baffle extends below the front baffle, to facilitate circulation of air between the display chamber and the cooling compartment, and pivotal means associated with the duct means near the lower end thereof to permit pivotal movement of the said structure as a unit to an inoperative position to gain access to the cooling means from the front of the show case.
4. In a refrigerated show case, the combination of a display chamber open at the top for access to the contents of the chamber, a cooling compartment positioned within the show case in a position above and to the rear of the display chamber, cooling means including refrigerant tubes mounted in said cooling compartment, duct means leading from the rear of the display chamber to the front of the cooling compartment for conveying air from display chamber to the cool-

ing compartment, said duct means including an integral structure having spaced parallel baffles extending longitudinally of the show case between the display chamber and the cooling compartment, supporting means for said structure including a pivotal mounting near the lower end, a releasable fastener near the upper end, whereby the structure may be pivoted as a unit away from operative position, upon release of said fastener, to provide access to the cooling means from the front of the show case.

5. A refrigerated show case, having in combination walls defining a display chamber open at the top to provide access to the contents of the display chamber, said walls including a rear wall extending above the access opening, a top wall 15 extending forwardly from the upper end of the rear wall, a skirt member depending from the top wall, a baffle structure releasably secured to the depending skirt and extending downwardly and rearwardly therefrom, the rear wall, top wall, depending skirt and baffle structure cooperating to define a cooling compartment above the display chamber, refrigerant tubes in said compartment, said baffle structure including spaced parallel baffle elements forming an air duct therebetween and extending longitudinally of the show case, and pivotal supporting means near the lower end of said baffle structure whereby it may be swung into an inoperative position over said access opening to expose the refrigerant tubes from the front of the show case.

6. A refrigerated show case, having in combination walls defining a display chamber open at the top to provide access to the contents of the display chamber, said walls including a rear wall extending above the access opening, a top wall extending forwardly from the upper end of the rear wall, a skirt member depending from the top wall, a baffle structure releasably secured to the depending skirt and extending downwardly therefrom, refrigerant tubes positioned between the baffle structure and said rear wall, said baffle structure including spaced parallel baffle elements forming an air duct therebetween and extending longitudinally of the show case, and pivotal supporting means near the lower end of said baffle structure whereby it may be swung into an inoperative position over said access opening to expose the refrigerant tubes from the front of the show case.

7. A refrigerated showcase, having in combination walls defining a display chamber open at the

top to provide access to the contents of the display chamber, said walls including a rear wall extending above the level of the access opening, a drawer slidably mounted for opening movement through the rear wall, means carried by the drawer for supporting articles in the display chamber, means associated with the upper portion of the rear wall defining a cooling chamber, and duct means for conveying air from the display chamber to the cooling chamber.

8. A refrigerated showcase, having in combination walls defining a display chamber open at the top to provide access to the contents of the display chamber, said walls including a rear wall extending above the level of the access opening, a drawer slidably mounted for opening movement through the rear wall, a perforated rack adjustably mounted in the drawer for supporting articles in the display chamber, means associated with the upper portion of the rear wall defining a cooling chamber, and duct means for conveying air from the display chamber to the cooling chamber.

9. A refrigerated showcase, having in combination walls defining a display chamber open at the top to provide access to the contents of the display chamber, said walls including a rear wall extending above the level of the access opening, a drawer slidably mounted for opening movement through the rear wall, a perforated rack mounted 25 in the drawer for supporting articles in the display chamber, means associated with the upper portion of the rear wall defining a cooling chamber, and duct means leading from the display chamber to the cooling chamber within the showcase whereby air may circulate between the chambers by passing upwardly from the display chamber through the duct means to the cooling chamber and passing downwardly from the cooling chamber into the display chamber and through the perforated rack.
